(57) **CLAIM**

The ornamental design for the portable skin care implement, as shown and described.

DESCRIPTION

FIG. 1 is a perspective view of the portable skin care implement of the subject invention;

FIG. 2 is a top view of the portable skin care implement of FIG. 1;

FIG. 3 is a right side view of the portable skin care implement of FIG. 1;

FIG. 4 is a bottom view of the portable skin care implement of FIG. 1;

FIG. 5 is a left side view of the portable skin care implement of FIG. 1;

FIG. 6 is a front end view of the portable skin care implement of FIG. 1; and,

FIG. 7 is a rear end view of the portable skin care implement of FIG. 1.

Details shown in broken lines are for illustrative purposes only, and form no part of the claimed design.
